M. F. F. WILSON

REVOLVER LOADING DEVICE

Filed Nov. 26, 1924

Mary F. F. Wilson ^{Inventor}

By John Boyle ^{Attorney}

UNITED STATES PATENT OFFICE.

MARY F. F. WILSON, OF NEW ROCHELLE, NEW YORK.

REVOLVER-LOADING DEVICE.

Application filed November 26, 1924. Serial No. 752,329.

To all whom it may concern:

Be it known that I, MARY F. F. WILSON, a citizen of the United States, residing at New Rochelle, in the county of Westchester and State of New York, have invented certain new and useful Improvements in Revolver-Loading Devices, of which the following is a specification.

My invention relates to a pistol reloading device and one of the objects of the invention is to provide a device whereby the chambers in the cylinder of a revolver may be quickly loaded with cartridges, and the reloading operation repeated several times.

Another object of the invention is to provide a suitable means for supporting the loading pack in a convenient position for use.

With these and other objects in view, my invention consists in certain novel and peculiar features of construction and combination of parts, as will be more fully described and particularly pointed out in the claims.

Fig. 1 is an elevation showing the loading pack in position for use;

Fig. 2 is a longitudinal section through the cylinder of the revolver and the loading pack;

Fig. 3 is a transverse section through the line 3—3 of Fig. 2; and

Fig. 4 is an enlarged detail view of Fig. 3.

The loading pack or carrier 1 comprises an outer casing 2 of such length as to contain several superposed clips of cartridges 3. The casing 2 may be made of any suitable shape and as shown is provided with flutes 4 running longitudinally thereof. The external contour of the cartridge clips 3 are fluted so as to closely fit the casing.

The clip is a ring of suitable material having openings 5 for receiving the heads 6 of the cartridges 7. When in position, the heads of the cartridges lie flush with the top of the clip. Between the cartridges, the clip is provided with inwardly projecting portions 8 for a purpose to be hereinafter specified.

The casing 2 is provided with a head piece 2' which is grooved at 9 to fit a complementary shaped spring clip 10 secured to the waist line belt 11 so that the casing will be normally worn in an inclined position, so as to facilitate quick loading.

Secured centrally to the head piece 2' is the tubular guide member 12 and sliding telescopically therein is the plunger 13, a coil spring 14 being interposed between the member 12 and the plunger 13, so as to keep the said plunger normally in extended position. A pin 15 carried by the plunger 13 engages a slot 15' for limiting the relative movement of the said plunger and member. Secured near the lower end of the plunger 13 are a pair of bowed leaf springs 16 and resting on the bowed portion 17 of the said springs are the projecting portions 8 of the cartridge clips 3.

Slidably mounted in the casing 2 is a block of lead 18 which rests in contact with the uppermost clip of cartridges.

The casing having been loaded with the several clips of superposed cartridges, the lowermost clip will be held in position by the springs 16, as shown in Fig. 2. When it is desired to load the revolver 19, the cylinder 20 is swung into position so that the head 21 of the plunger 13 will engage the central pin 22 of the cylinder 20. By pulling back the revolver towards the casing, the plunger 13 will telescope into the guide member 12 and the leaf springs 16 will ride by the lowermost clip of cartridges, thereby releasing them from the casing, whereupon they will drop into the chamber of the revolver. Due to the weight of the lead block, the remaining clips will be fed forward to the front end of the casing. In the subsequent loading operations, the remaining clips of cartridges will be held against upward movement by the weight of the lead block as the plunger 13 moves upward.

I claim:

1. A loading pack for revolvers comprising a casing, means for supporting a clip of cartridges therein, and means for releasing the said clip by engagement with the cylinder of the revolver.

2. A loading pack for revolvers comprising a casing, means for supporting a plurality of clips of cartridges therein and means for releasing a single clip of cartridges at one time by engagement with the cylinder of a revolver.

3. A loading pack for revolvers comprising a casing, superposed clips of cartridges therein, a reciprocating plunger in the cas-

ing, means carried by the plunger for engaging a clip of cartridges, the said means releasing a clip of cartridges by engagement of the plunger with the cylinder of a revolver.

5. 4. A loading pack for revolvers comprising a casing, superposed clips of cartridges therein, a reciprocating plunger, spring

members carried by the plunger for engaging a clip of cartridges, and means for disengaging the spring members from the clip, ¹⁰ by engagement of the plunger with the cylinder of a revolver.

In testimony whereof I affix my signature.

MARY F. F. WILSON.
